COLLAPSIBLE CHAIR FOR BABIES

Nancy C. Sperry, Springfield, Ill.

Application December 22, 1952, Serial No. 22,803

Term of patent 7 years

(Cl. D15—1)

Fig. 2.

Fig. 1.

To all whom it may concern:

Be it known that I, Nancy C. Sperry, a citizen of the United States and a resident of the city of Springfield, county of Sangamon, and State of Illinois, have invented a new, original, and ornamental Design for a Collapsible Chair for Babies, of which the following is a specification, and reference being had to the accompanying drawings forming a part thereof.

Fig. 1 is a front perspective view of a collapsible chair for babies showing my new design.

Fig. 2 is a collapsed view of the same.

Fig. 3 is a front view of the same.

Fig. 4 is a side view of the chair.

I claim:

The ornamental design for a collapsible chair for babies, as shown.
